Primary Examiner—Theodore M. Shooman*Assistant Examiner*—Paula Mortimer*Attorney, Agent, or Firm*—Brooks & Kushman[57] **CLAIM**

The ornamental design for a hood, as shown and described.

DESCRIPTION

FIG. 1 is a perspective view of a hood showing my new design;

FIG. 2 is a top plan view thereof;

FIG. 3 is a right side elevational view thereof;

FIG. 4 is a front elevational view thereof;

FIG. 5 is a left side elevational view thereof; and,

FIG. 6 is a rear side elevational view thereof.

The broken line showing of the shirt in FIG. 1 and the letter "W" and stripes in FIGS. 1-6 is for illustrative purposes only and forms no part of the claimed design.
